KEY-LEVER SPRING-LOCK.

1,384,088.

Specification of Letters Patent. Patented July 12, 1921.

Application filed February 4, 1918. Serial No. 215,228.

To all whom it may concern:

Be it known that we, ADOLPH J. PRUSZYNSKI and ALFRED O. H. EBERT, citizens of the United States, residing at Chicago, in the county of Cook and State of Illinois, and at Woodstock, in the county of McHenry and State of Illinois, respectively, have invented certain new and useful Improvements in Key-Lever Spring-Locks, of which the following is a specification.

This invention relates more particularly to the key lever construction of a typewriter and to the means for pivotally mounting and adjusting the spring tension which is applied to the key lever.

The invention consists in the novel construction, combination and arrangement of the parts.

In the accompanying drawing—

Figure 1 is a side elevation of a key lever with a sectional view of the pivotal mounting and spring tension adjustment parts;

Fig. 2 is a sectional view taken on line 2—2 of Fig. 1.

It is necessary to provide an adjustment of the means for varying the spring tension of typewriter key levers so that they may be uniformly operated, and it is desirable to provide a convenient means, not only for varying the tension applied to the key levers, but also for insuring that this tension will be maintained. The principal object of the invention, therefore, is to provide a yielding pressure plate which bears upon the spring tension adjustment screws for holding the screws in any adjusted position and to prevent their dislodgment under continued operation of the key levers.

In the accompanying drawing, the numeral 1 designates generally a typewriter frame in which there is positioned a sub-frame having a key lever pivoting frame part 2 and a frame part 3 in which are pivoted the type-bar sub-levers 4.

The frame part 2 is formed with an up-standing portion 5, in which are vertical slots 6, with a horizontal groove 7 opening from the rear and extending transversely of the slots 6 for seating a pivoting wire 8. In line with each of the slots 6 is a vertical perforation 9, having a beveled upper edge

10, and a lower threaded portion 11 in which an adjusting screw 12 is movable. A plurality of key levers 13 are disposed in the slots 6, and the rear end of each key lever is formed with a substantially vertical pivoting slot 14 which engages the pivoting wire 8. The key levers are maintained in an upright position by the slots 6 in which they are pivoted at the rear end and by a slotted comb 15 adjacent the forward extremity thereof, and each one has a pin 16 for actuating its sub-lever 4, in a well-known manner.

Interposed between each key lever 13 and its tension adjusting screw 12 is a spring 16, the lower end of which is seated in recess 9, and the upper end of which engages a projection 17 formed on the lower edge of the key lever for that purpose. This spring will normally hold the key lever upon its pivot 8, but in order to insure that the key lever will not be disengaged from the pivot a guard plate 18 is attached by means of screws 19 to the frame portion 2 just below the lower edge of the key lever beneath the pivot wire 8 so that any abnormal depression of this end of the key lever is prevented by the guard plate, but so that the guard plate offers no obstruction whatever to the ordinary pivotal action of the key lever.

Along the front edge of the frame part 2 is a ledge 20, and the upper edge of a pressure plate, having a plurality of spring tongues 22, is applied to this ledge so that the extremity of each tongue bears against the lower end of one of the adjusting screws 12, and as this pressure plate is preferably of spring metal, the tongues may be pressed against all of the adjusting screws in unison by means of a clamping plate 23 which forces the pressure plate 21 against the ledge 20 and the tongues 22 thereof against the extremities of the screws 12. The tongues being resilient it is obvious that any screw can be separately adjusted by means of a screw-driver without relieving the tension of the pressure plate; the tension of the tongues is such that the screws are held in place in any adjusted position. This tendency to become loose arises mostly under operating conditions due to the continued op-

eration of the key levers, but if a slight pressure is placed upon the screws, such as that given by the spring tongues 22, they exhibit no tendency whatever to become loose, but will remain fixed in any position to which they are adjusted, so that the tension placed on the springs 16 may be varied and maintained as desired.

It is obvious that instead of making either 10 the pressure or clamping plates 21 and 23 apply to all of the adjustment screws they may be made in sections, and the same is also true of the guard plate 18. It is also obvious that each screw can be rotated a whole or any 15 part of a turn and will be held yieldingly from movement in the adjusted position.

We claim:—

1. In a typewriter, a plurality of key 20 levers, a tension spring for each of said key levers, an adjusting screw for each of said tension springs, and resilient means for separately holding each of said adjusting screws in various positions of rotation, said resilient means comprising a plurality of 25 spring tongues, one for each screw, each tongue being arranged to engage its respective screw at one side thereof and to exert pressure laterally on said screw.

2. In a typewriter, a plurality of key 30 levers, a tension spring for each of said key levers, an adjusting screw for each of said tension springs, and resilient means for separately holding each of said adjusting screws in various positions of rotation, said 35 resilient means comprising a plurality of U-shaped spring tongues, one for each of said screws, each of said tongues having its lateral face at the free end thereof arranged to engage the side of its respective screw and 40 to exert lateral pressure on said screw.

3. In a typewriter, a plurality of pivoted 45 key levers, a perforated frame part having slots in which the levers are pivoted, an adjusting screw in the frame part for each 50 lever, a tension spring between each screw and its corresponding lever, and a member with separate spring tongues one for engaging the end of each screw to hold it yieldingly in any adjusted position, each of said 55 tongues being arranged with a lateral face thereof resiliently held against one of said screws.

4. The combination with a frame part 60 having an upper slotted portion and perforations in line with the slots, of key levers pivoted in the slots and overlying the perforations, adjusting screws threaded in the perforations and projecting therefrom, springs interposed between the screws and 65 the levers, and means for holding the screws in adjusted positions comprising a plate with a plurality of resilient tongues, one for engaging each screw, each of said tongues being arranged with a lateral face thereof 70 pressed against its respective screw,

5. In a typewriter, pivoted key levers, tension springs and adjusting screws therefor, and a plate with a plurality of spring tongues, one for engaging each of the adjusting screws to hold them in any rotatable 75 position, each tongue having a lateral face thereof resiliently held against its respective adjusting screw to hold said screw in any position of rotation.

6. In a typewriter, pivoted key levers, tension springs and adjusting screws therefor, a plate with a plurality of spring tongues, one for each of the adjusting screws, and means for clamping the plate with the 80 tongues against the screws, each tongue having a lateral face thereof resiliently held against its respective adjusting screw to hold said screw in any position of rotation.

7. In a typewriter, key levers, a frame part in which the levers are pivoted having 85 perforations below the levers which are beveled at the edge adjacent the levers, and coil springs disposed in the perforations and bearing against the levers, the beveled edges preventing the springs from catching the 90 edges when the levers are operated.

8. In a typewriter, the combination with 95 a frame part, key levers pivoted therein, tension springs and adjusting screws therefor projecting from the frame part, a member with a plurality of spring tongues bent over at the end and adapted to engage the ends of the screws, and a clamping plate for pressing said member so that the tongues 100 yieldingly engage the screws.

9. The combination with key levers, of a frame part in which they are pivoted having underlying perforations and a ledge at the front, tension springs and adjusting screws for the levers in said perforations, a 105 tension plate having tongues for engaging said screws with the opposite edge engaging said ledge, and a clamping plate which presses the said tension plate against said ledge and the tongues thereof against the 110 screws.

10. In a typewriter; a frame part having an upwardly extending slotted portion, with a horizontal groove extending across the slots; a key lever disposed in the slot having a substantially vertical pivoting slot; a pivot therefor seated in said groove; a tension adjusting means for the lever comprising a spring, an adjusting screw and means including a spring-tongued plate for holding the screw in any rotatably adjustable position, the tongues of said plate being arranged with their lateral faces resiliently pressed against their respective screws; and means for preventing the disengagement of 115 the lever from its pivot.

11. The combination with key levers, of a frame part in which they are pivoted having underlying perforations and a ledge at the front, tension springs and adjusting screws 120

100

for the levers in said perforations, and resilient means engaging the said ledge and separately engaging the ends of the screws to bind them yieldingly in place, said resilient means comprising U-shaped tongues each having its end arranged to press laterally against one side of one of said screws.

In testimony whereof I have signed my

name to this specification, on this 30th day of January, A. D. 1918. ¹⁰

ADOLPH J. PRUSZYNSKI.

In testimony whereof I have signed my name to this specification, on this 1st day of January A. D. 1918.
